UNITED STATES PATENT OFFICE

ALFRED G. SPINDLER, OF PITTSBURGH, PENNSYLVANIA

DESIGN FOR A COMBINED BIRD BATH AND SUN DIAL

Application filed May 14, 1932. Serial No. 43,809. Term of patent 14 years.

To all whom it may concern:

Be it known that I, ALFRED G. SPINDLER, a citizen of the United States, residing at Pittsburgh, in the county of Allegheny and State of Pennsylvania, have invented a new, original, and ornamental Design for a Combined Bird Bath and Sun Dial, of which the following is a specification, reference being had to the accompanying drawing, forming part thereof.

Fig. 1 is a perspective view of a combined

bird bath and sun dial showing my new design; and

Fig. 2 is a side view of the combined bird bath and sun dial of Fig. 1 showing the contour thereof.

I claim:

The ornamental design for a combined bird bath and sun dial, substantially as shown.

In testimony whereof I have hereunto subscribed my name this 13th day of May, 1932.

ALFRED G. SPINDLER.
